ATTORNEY

UNITED STATES PATENT OFFICE

JOSEPH H. BUHRIE, OF YUKON, PENNSYLVANIA

TOY

Application filed January 28, 1929. Serial No. 335,590.

This invention relates to new and advantageous improvements in toy pistols for discharging rubber bands and like projectiles.

5 An object of the invention comprehends the provision of a sight for the article of ordnance.

Another object of the invention contemplates a slide mounting for the sight.

10 An additional object of the invention consists of a trigger construction for the toy engageable with the projectile carried by the sight.

With the above and other objects in view, 15 the invention further consists of the following novel features and details of construction, to be hereinafter more fully described, illustrated in the accompanying drawing and pointed out in the appended claims.

20 In the drawing:—

Figure 1 is a side elevation of my invention.

Figure 2 is a top plan view thereof.

25 Figure 3 is a rear end elevation of the invention.

Figure 4 is a vertical horizontal sectional view taken on line 4—4 of Figure 1.

Referring to the drawing in detail wherein like characters of reference denote corresponding parts, the reference character 30 10 indicates the handle or stock of a toy article of ordnance having a barrel 11 and which is adapted to simulate, in effect, an automatic pistol. The sight, such as indicated at 12, for the toy pistol, is raised for an appreciable distance above the upper surface of the barrel 11 as best shown in Figure 4 of the drawing.

40 An extension or tongue 13 carried by and depending from the under surface of the sight 12 is projected and slidably mounted within a channel portion 14 longitudinally disposed within the upper side of and adjacent the outermost extremity of said barrel. A compression spring 15, carried within a socket opening 16 in the barrel 11 and in communication with one end of the channel 14, is engaged at its opposite end with 45 50 the adjacent end of the extension or tongue

13 for the sight 12, substantially as illustrated in Figure 2 of the drawing.

A lug 17, of elongated flattened formation, is extended horizontally through the tongue or extension 13 and has its respective 55 ends projected for appreciable distances beyond the outer surfaces of said extension for final disposition within elongated slots or raceways 18 in the barrel 11 and especially those portions thereof forming the side 60 walls of the channel or groove 14.

From the foregoing, it will be noted that a slide mounting is provided for the sight and which is induced, by the tension of the spring 15, to occupy a position adjacent the 65 forward end of the channel.

The trigger construction comprises a trigger arm or lever 18' pivotally mounted, as indicated at 19, between spaced ears 20 projecting for appreciable distances beyond the rear 70 side edge of the butt, stock or handle 10, and preferably at an intermediate point in the length thereof. A spring leaf 21, carried upon the butt or handle 10 between the ears 20, is bent upon itself and sprung at its opposite end against the inner surface or side of the lever or trigger 18', in the manner shown in Figure 1 of the drawing. Necessarily, the opposite and free end of the lever or trigger 18' is forced or otherwise induced against the corner or point of intersection between the butt or handle and the barrel. A rubber band, in the form of a strip or of annular formation, as indicated at 22, is initially looped about the forward 75 end of the sight 12 whereas the remaining rearwardly extending extremities thereof are arranged in overlapping relation upon the upper side of the barrel 11 adjacent the handle, stock or butt 10 for interposition between the aforementioned contacting end of the trigger or lever 18' and the adjacent side of the handle.

The present invention offers several added features, in view of toys of like nature now in use, namely, the trigger construction teaches the modern trigger squeeze whereby a gradually compressing action by the hand of the operator and against the trigger or lever 18' will release the aforementioned 80 85 90 95 100

overlapping ends or yoke portion of the band located between the adjacent ends of the lever and handle of the pistol. Furthermore, a sight for the pistol not only facilitates the aiming of the pistol to discharge the projectile at a desired point, but which also serves the purpose of holding and providing means to stretch the band or projectile.

- 10 The major advantage and utility, however, for the sight resides in the provision of the sliding mountings therefor which, due to the spring tension exercised thereagainst, will in turn coact with the releasing of the trigger to shove or eject the projectile or band with an added amount of pressure in addition to the rebound action incident to the elastic qualities inherent in the projectile per se whereby the aforesaid projectile will 15 be discharged for greater distances.

20 The spring 15 is of such strength that upon the releasing of the trigger and projectile, the sight 12 will slide upon the upper side of the barrel 11, incident to the slide 25 mounting therefor and abut the forward end wall of the channel or groove 14 with such velocity that a loud report will ensue likened to that of a cap pistol or blank cartridge.

25 The invention is susceptible of various changes in its form, proportions and minor details of construction, and the right is herein reserved to make such changes as properly fall within the scope of the appended 30 claims.

35 Having thus described the invention, what is claimed is:—

1. In a toy pistol comprising a stock including a barrel, said barrel having an elongated groove within the upper side and adjacent the outermost end thereof, a sight, an extension carried by the sight slidably mounted within the groove, a compression spring carried within the groove and engageable with said sight, and a trigger carried upon the stock of the pistol to release the adjacent portions of an elastic projectile stretched from the sight.

2. A toy pistol comprising a stock having a barrel, said barrel having a groove within its upper side and adjacent the outermost projecting end thereof, a sight for the barrel, a tongue carried by and depending from the sight slidably mounted within said groove, the side walls of the groove within the barrel being slotted, a lug carried by the tongue having its ends projected through the slots, a compression spring arranged within the rearmost end of the groove and engageable with the adjacent end of the tongue to normally induce the sight within the forward end of the groove, and a trigger carried upon the stock and engageable with the adjacent portions of elastic projec-

75 tiles stretched from the sight against the tension of the compression spring.

70 In testimony whereof I affix my signature.

JOSEPH H. BUHRIE.
